UNITED STATES PATENT OFFICE

2,537,841

COTTER KEY

John A. MacLean, Jr., Winnetka, Ill., and
Benjamin Franklin Money, Tulsa, Okla.

Application August 30, 1945, Serial No. 613,578

1 Claim. (Cl. 85—8.5)

1

Our present invention relates to cotter keys and particularly to those of a type having a plurality of surfaces offset from one another and adapted forcibly to engage the wall of an appropriate cotter-receiving opening, whether of normal or somewhat over-size, thereby to prevent rattling of the cotter key and the resultant wear of both the cotter key and the wall of the opening.

In general, it is an object of our invention to provide a cotter key having leg portions offset from one another in a manner and at a position such that said portions forcibly engage the wall of a normal or oversize cotter-receiving opening and flex relatively as a result of resiliency and/or deformation to compensate for the size of the opening.

As is usual, the cotter key presently contemplated has two adjacent legs joined by an integral head loop, but additionally and distinctively has two portions of the adjacent legs offset from one another, so that the legs remain adjacent with their ends in parallel relationship and connected by angularly disposed and adjacent intermediate portions.

It is another object of this invention to provide an improved cotter key characterized by a reversely bent intermediate portion in each of the legs, such that each of the legs has parallel portions offset sidewise with one portion remaining aligned with the head loop, while the other portion is parallel to and offset from such alignment.

Other objects and advantages of our invention will appear from the following detailed description, wherein reference is made to the accompanying drawings.

Referring to the single sheet of drawings,

Figs. 1, 2, and 3 are, respectively, side, top, and end elevational views of a preferred form of our improved cotter key as it appears before being placed in the cotter-receiving opening of a bolt, pin, or other part with which it is adapted to be used; and

Fig. 4 is a top elevational view of a cotter key of the type shown in Fig. 1 when installed in the opening of a part which is indicated in section.

Referring to the structure of the exemplary embodiment of our cotter key shown in Figs. 1 to 4, inclusive, of the drawings, it comprises a piece of normally half-round metal wire which has been return-bent and formed to define a head loop 10 with legs 12 and 13 projecting therefrom in adjacent and closely spaced relation. One leg, such as the leg 12 of the illus-

2

trated embodiment, is desirably somewhat longer than the other to facilitate the separation of the legs after the installation of the cotter key. The substantially flat faces of the half-round wire stock face inwardly and lie adjacent one another as well as forming the inner surface of the head loop. The material used in the wire stock is desirably steel, such as that which has been found suitable for cotter keys and which possesses some resilience and the capability of deformation.

Either before or after, and preferably after, the formation of the cotter key from the half-round wire stock, the legs 12 and 13 are deformed by reverse bends 12a, 12b, 13a, and 13b so that their opposite end portions are offset from one another and parallel. Both legs being bent in like manner and crosswise of the adjacent flat surfaces thereof, the legs remain in adjacent and juxtaposed relation throughout their length. The position of the bends, in addition to being intermediate the ends of the legs, is desirably near the head loop and such that when the cotter key is installed in a cotter-receiving opening of a part with which it is used, as shown in Fig. 4, both bends of the legs fall within the confines of the cotter-receiving opening.

In order to limit the necessary axial length of a cotter-receiving opening which is adapted to coact with the cotter key in the desired manner, the bends are preferably close together. To facilitate the insertion of the cotter key into an appropriate cotter-receiving opening the angularity of the reverse bends is such that the angularly disposed connecting portions of the legs between the reverse bends have gradual slopes and curvatures between the end portions of the legs. Because of the desired limitation of the separation between the reverse bends and the gradual slope of the angularly disposed intermediate portions it has been found desirable to limit the offset relationship of the end portions of the legs in most instances to less than half the width of the legs. Such a limitation of the offset relationship still leaves a wide variation in the sizes of cotter-receiving openings into which the disclosed cotter key will firmly fit. It also provides a cotter key structure which is adapted to the necessary deformation for a forced fit in a relatively small cotter-receiving opening.

Since the reverse bends 12a, 12b, 13a and 13b in the two legs of the cotter key are crosswise of the flat surfaces of the adjacent legs, both legs individually seat themselves and engage the wall of a cotter-receiving opening, such as 14, in

a cotter-receiving part 15, as depicted in Fig. 4. When forced into the cotter-receiving opening 14, the convexly curved portions on opposite sides of each of the legs forcibly engage the wall 5 of the opening and effect a sufficient deformation of the cotter key to permit the insertion, although maintaining a forced fit. In addition to the engagement of the convexly curved portions, additional side surfaces of one or both of the end portions of the legs also engage the wall 10 of the cotter-receiving opening in most instances. Such forcible engagement of each of the cotter key legs with the wall of the cotter-receiving opening at a plurality of separated positions insures the prevention of rattling of the cotter key 15 in the opening and movement of the key that would result in wear. The spreading of the ends of the cotter key legs in the usual manner serves additionally to hold the cotter key in its position within the opening.

Although there are various ways in which a cotter key of the disclosed type might be made in the present instance, it is preferred that the deformation comprising the reverse lateral bends 12a, 12b, 13a, and 13b shall be accomplished after 25 the formation of the cotter key into its adjacent legs and the adjoining head loop. One manner of accomplishing the desired deformation is by bending the legs in a suitable die in a punch press.

While we have illustrated a preferred embodiment of our invention, many modifications may be made without departing from the spirit of the invention, and we do not wish to be limited to the precise details of construction set forth, but 35 the desire to avail ourselves of all changes within the scope of the appended claim.

Having thus described our invention, what we claim as new and desire to secure by Letters Patent of the United States, is:

A cotter key adapted forcibly to engage the

wall of an appropriate cotter-receiving opening at a plurality of spaced positions and in transverse planes and comprising, in combination, a pair of legs made of half-round wire stock and extending in adjacent and juxtaposed relationship from an integral head loop with the flat sides of the half-round stock facing one another, said head loop having substantially plane side faces and merging with the legs through smoothly curved portions, the mid-portions of said legs being bent in the same manner near the head loop in directions paralleling and lateral to the flat sides of the legs and at like positions so that substantially coplanar surfaces of the legs lie adjacent one another along the full length of one of the legs, the end portions of the legs on opposite sides of the bends being substantially parallel and in offset relationship to one another, the end portions of the legs remote from 20 the head loop being offset from the planes of the head loop side faces, so that when driven into a cotter-receiving opening the offset portions bind on sides of the opening in directions lateral to those engaged by said curved portions.

JOHN A. MACLEAN, JR.
